(57) **CLAIM**

The ornamental design for a clasp, as shown and described.

DESCRIPTION

FIG. 1 is a front perspective view of a clasp, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective exploded view thereof;

FIG. 10 is a bottom perspective exploded view thereof; and, FIG. 11 is a perspective view showing the clasp in a position of use with environment.

The broken lines in the drawings illustrating portions of the clasp form no part of the claimed design. The broken lines in FIG. 11 illustrate environmental structure of the clasp and form no part of the claimed design.
